(57) **CLAIM**

The ornamental design for a probe for electromyograph, as shown and described.

DESCRIPTION

FIG. 1 is a front, right-side, top perspective view of the probe for electromyograph, showing the new design; FIG. 2 is a front elevational view thereof; FIG. 3 is a left-side elevational view thereof; FIG. 4 is a top plan view thereof; and, FIG. 5 is a bottom plan view thereof.
The broken lines depict parts of the probe that form no part of the claimed design.
